CLAIM

The ornamental design for a cutting board and tray, as shown and described.

DESCRIPTION

FIG. 1 is an exploded perspective view of the cutting board and tray of my new design showing the cutting board, tray and holder;

FIG. 2 is a perspective view of the assembled cutting board and tray of my new design with the cutting board inserted into the tray and assembled into the holder;

FIG. 3 is a right side elevational view of the assembled cutting board and tray of my design, the left elevational view being a mirror image thereof;

FIG. 4 is a front elevational view of the assembled cutting board and tray of my design, the rear elevational view being a mirror image thereof;

FIG. 5 is a top plan view of the assembled cutting board and tray of my design; and,

FIG. 6 is a bottom plan view of the assembled cutting board and tray of my design.
